UNITED STATES PATENT OFFICE.

PRESTON STURGES, OF BROOKLYN, NEW YORK.

PROCESS FOR MAKING ENGRAVED PLATES.

Application filed March 24, 1924. Serial No. 701,603.

To all whom it may concern:

Be it known that I, PRESTON STURGES, a citizen of the United States, and a resident of Brooklyn, in the county of Kings, city and State of New York, have invented a certain new and useful Process for Making Engraved Plates, of which the following is a specification.

The invention relates to a process for making engraved plates for cards, wedding invitations, announcements or any other purpose. Ordinarily, these plates are made on copper and are cut or engraved by hand. Naturally this requires very expert workmanship to get good results, thus making the plates quite expensive.

In this process some of the well known principles of photo-engraving are used and a plate is obtained that is not only cheap in cost but better and more accurate than even a very skillful artist could produce.

Further advantages of the process will be brought out in the following specification and illustrated in the drawings forming a part thereof. In said drawings:

Fig. 1 is a perspective view of one of the master blocks on which the letters or numerals of any desired style are placed;

Fig. 2 is a perspective view of one of the prints that are made from the master blocks;

Fig. 3 is a perspective view of the board on which the prints are mounted preparatory to being photographed;

Fig. 4 is a side elevation of the board and the camera by which the subject-matter to be engraved is photographed; and

Fig. 5 is a fragmentary detail sectional view of the finished plate after being treated with acid.

The reference numeral 10 denotes one of a series of master blocks, each one of which bears a letter of the alphabet or a numeral. On these blocks the letters or numerals are in white and the background in dead black, the hatching on the drawing denoting the black. A number of sets of these master blocks may be made each one bearing the letters and numerals in different styles of printing.

These master blocks will be photographed, and from the negatives as many prints of each letter or numeral as desired will be made, preferably on a sensitized material, which is flat, unbreakable and cheap. On these prints 11 the background will be dead

black and the letter or numeral will be white, as on the master block 10. If the surface of these prints should become marred around the edges or elsewhere, they may very easily be touched up with black paint.

Attention is now directed to Fig. 3, where a board 12 is shown, on which is mounted the desired subject-matter for the finished engraved plate. The prints 11 for said subject-matter are selected and arranged on strips 13 which are mounted in grooves 14 on the board. A plurality of these grooves 14 are shown so that the strips 13 may be spaced apart in any desired relation to each other. This entire board and the strips are dead black. The prints and the board being black and the letters white, when they are photographed on a sensitized plate there will be no lines of division or demarkation between the letters. The method of adjusting the strips different spaces from each other might be accomplished in numerous different ways. The grooves could readily be eliminated and any means of adjusting or moving the strips adopted.

The next step consists in mounting the board 12 with the subject-matter thereon in any convenient way on a table or stand 15. As illustrated in Fig. 4, this is accomplished by a bracket 16. A photo-engraver's camera 17 is placed at the proper distance from the board 12 and is tilted so that the plate in the camera is parallel with the board. The subject-matter on the board is then photographed on the sensitized plate in the camera. From this plate or negative the subject-matter is then transferred to a plate made of copper or any other suitable material.

The plate is then etched or treated with acid and the acid will eat away the white letters and leave the rest of the plate smooth and perfect.

A flat plate adapted to be used for engraving is then produced, with the lettering sunk below the surface as indicated at 19 in Fig. 5.

As suggested heretofore numerous changes might be made in the details without departing from the spirit of the invention or the scope of the claim.

What I claim as new is:

A process for making engraved plates comprising photographing a series of master blocks having thereon the letters of the alphabet and numerals, the letters and

numerals being white and the background of the blocks black, from the negatives thus produced preparing a number of prints on thin flat sensitized material, the letters and numerals on the prints being white and the background black, setting up on a black background a sufficient number of these

prints to form the subject-matter for the plate to be engraved, photographing the same, transferring it from the negative thus produced to a sensitized plate of suitable material, and treating the plate with acid to etch it.

PRESTON STURGES.
